UNITED STATES PATENT OFFICE.

THEOPHILOS ZACHARIADIS, OF LONDON, ENGLAND.

APPARATUS FOR DRAWING AND TWISTING SLIVERS AND THE LIKE.

Application filed May 12, 1923. Serial No. 638,515.

To all whom it may concern:

Be it known that I, THEOPHILOS ZACHARIADIS, a subject of the King of Greece, and residing at London, England, have invented 5 certain new and useful Improvements in and Relating to Apparatus for Drawing and Twisting Slivers and the like, of which the following is a specification.

This invention relates to machinery for 10 the preparation of yarn for subsequent spinning in a spinning frame and has for its object the provision of a machine or series of machines which will accept a loose bundle of fibres, such as a sliver, and deliver a yarn 15 of any desired size suitable for the spinning mill, such machine being entirely automatic and continuous in action, the material to be treated being completely covered in during the process and demanding no manual attention.

The invention mainly consists in the provision of apparatus for automatically and continuously reducing the cross-sectional area of a sliver or roving consisting of a 25 bundle of fibres to any desired degree, and at the same time imparting to such sliver or roving any desired degree of temporary twist.

The invention also consists in apparatus 30 as hereinafter indicated.

The following is an example of a machine constructed according to the invention.

In the accompanying drawings:

Figure 1 is a sectional view of the machine on the line 1—1 of Figure 2;

Figure 2 is a sectional view of the machine in an axial plane at right angles to the axes of the rollers;

Figure 3 is a cross-sectional view on line 2—2 of Figure 2.

Fig. 4 is a diagrammatic view showing a plurality of machines connected together.

The same figures refer to the same parts 45 in each view.

Each machine includes two pairs of rollers 1 and 2, 3 and 4 arranged, as shown, with their centres at the corners of a parallelogram; the members 1 and 2 of one pair 50 of rollers rotate in opposite directions at equal speeds, while the members 3 and 4 of the other pair also rotate in opposite directions at equal speeds, but slower than the speed of the rollers 1 and 2. The distance

between the pairs is dependent on the length 55 of the individual fibres of the material to be drawn.

The rollers are carried in a frame 13, 14 and connected together by toothed wheel gearing 5, 6, 7, 8, 9, 10 in such a manner 60 that the corresponding elements 1 and 3 of each pair rotate in the same direction. Two split bearing brackets 11, 12 each carrying one roller of each of the pairs are connected to the frame in such a way as to urge the 65 two rollers of each pair into mutual contact by means of spring bolts 32.

The frame member 14 has a sector-shaped extension 35 which fits inside the casing 15 and serves as a support for the weight of 70 the frame and rollers.

The frame member 14, together with the rollers and their gearing, is pushed within and connected rigidly by means of spring pins 33 to the interior of a cylindrical box-shaped casing 15 which is adapted to be closed by a lid 16 carrying a tubular shaft 17 at its centre, in such a way that the axes of the rollers are at right angles to the axes X—X of the box. A second tubular shaft 80 18 which is arranged coaxially with the first tubular shaft, projects through the box end and forms a bearing on which the end 19 of the box-shaped casing can rotate, and is itself arranged to rotate in a further bearing 85 20, the second bearing 21 for the casing 15 being provided around the first tubular shaft 17. A spur wheel 22, coaxial with the tubular shafts 17, 18, is attached rigidly to the end of the casing nearest the second tubular shaft 18, and a second spur wheel 23 is attached rigidly to the second tubular shaft. These two spur wheels are adapted 90 to be driven at different speeds by a common shaft 24 carrying two spur wheels 25 95 and 26. The second tubular shaft, at its end which enters the box-shaped casing, is connected by suitable spur and bevel gearing 27, 28, 29, 30, 31, arranged inside the casing to one end of the roller 2. As a consequence 100 of the differing speeds of the casing and the second tubular shaft 18, rotation of the common driving shaft 24 causes rotation of the casing 15 and the frame 13, 14 carrying the rollers and also rotation of 105 the rollers about their axes. By suitable selection of the gearing it is clear that any desired ratio between the speed of the rollers

around their axes and the speed of the casing around its axis may be obtained.

In operation the sliver or roving to be prepared enters the casing through the tubular shaft 17 and is engaged by the first pair of rollers 3, 4; it then bridges the gap between the two pairs of rollers, and passes through the second pair of rollers 1, 2. The speed of the second pair of rollers is arranged to exceed the first pair in the same ratio as the desired reduction of cross sectional area of the bundle of fibres, and the arrangement of the roller-centres in a parallelogram, which allows of a larger arc of contact of the fibres on the rollers, provides good security against breakage of the sliver or roving and results in a more uniform draft. During the passage of the sliver or roving through the rollers the casing 15 together with the rollers rotates about its axis and imparts a twist to the sliver during the drawing process.

The sliver or roving, guided by a hollow cone 34, subsequently emerges in its reduced and twisted state through the hollow shaft 18.

A number of similar machines may be arranged in series in the same axial line and with a common driving shaft, so that the hollow shaft 18 of one machine enters the hollow shaft 17 of the next machine, and a proportionate reduction and twist of the sliver may be made in each elementary machine until the desired reduction, for instance for the spinning of thread, is completed. It will be noted that the whole preparation and delivery of the yarn to a final spinning machine is carried out automatically, continuously, and without exposure.

Such a machine may be used for various purposes such as the preparation of fibre for rope, twine and the like.

It is of course understood that more than two pairs of rollers may be arranged in each machine if desired, and the axes of the machines may be arranged horizontally, vertically, or inclined at any suitable angle.

Having now particularly described my in-

vention what I claim as new and desire to secure by Letters Patent is:—

1. Apparatus for automatically and continuously reducing the cross-sectional area of a loose bundle of fibres or the like to any desired degree by simultaneously drawing and temporarily twisting the material acted upon, including a hollow shaft, a frame arranged to rotate on said hollow shaft about its longitudinal axis and a plurality of rollers carried in said frame and having parallel axes transverse to the axis of the frame, the rollers being geared together in pairs in such a manner that the corresponding members of each pair rotate in the same direction at different speeds, while the individual members of each pair rotate in opposite directions at equal speeds, and means for rotating simultaneously all said rollers about their axes and said frame about its longitudinal axis, the plane containing the axes of one pair of rollers being parallel to the plane containing the axes of the adjoining pair of rollers and both said planes being inclined to the longitudinal axis of the frame.

2. Apparatus as claimed in claim 1 characterized by the feature that the frame of its attached gearing and the rollers is enclosed in a cylindrical casing.

3. Apparatus as claimed in claim 1, including a plurality of machines as claimed arranged with their longitudinal axes in line and arranged so that the hollow shaft of one frame connects in a suitable manner with the hollow shaft of the next frame.

4. Apparatus including a plurality of machines as claimed in claim 1 and a cylindrical casing enclosing the rollers and the frame with part of the attached gearing, the individual machines being arranged with their axes in line and with the hollow shaft of one machine connecting in a suitable manner with the hollow shaft of the next machine.

In testimony whereof I have signed my name to this specification.

THEOPHILOS ZACHARIADIS.
